UNITED STATES PATENT OFFICE.

JOHN R. JOHNSON, OF STEELE, NORTH DAKOTA.

GARMENT-STRETCHER.

1,177,631.

Specification of Letters Patent.

Patented Apr. 4, 1916.

Application filed May 5, 1915. Serial No. 26,063.

To all whom it may concern:

Be it known that I, JOHN R. JOHNSON, a citizen of the United States of America, residing at Steele, in the county of Kidder 5 and State of North Dakota, have invented new and useful Improvements in Garment-Stretchers, of which the following is a specification.

This invention relates to improvements 10 in garment stretchers and has particular application to a necktie stretcher.

In carrying out the present invention, it is my purpose to provide a device of the class described which may be readily and 15 conveniently inserted in the tie and which when placed in the tie and released will serve to stretch the fabric of the tie and so eradicate wrinkles.

It is also my purpose to provide a device 20 of the type set forth which will be found especially useful for stretching four in hand ties and which may be manufactured and marketed at small cost.

With the above and other objects in view, 25 the invention consists in the construction, combination and arrangement of parts hereinafter set forth in and falling within the scope of the claim.

In the accompanying drawing; Figure 1 30 is a view in side elevation of a necktie stretcher constructed in accordance with the present invention. Fig. 2 is a view in edge elevation thereof. Fig. 3 is an end view. Fig. 4 is a view similar to Fig. 1 showing 35 the device inserted in a necktie.

My improved necktie stretcher is preferably, although not necessarily, formed of a single strip of spring metal 1 bent upon itself centrally of its ends as at 2 and having 40 the limbs 3, 3 thereof spaced apart, the limbs being spaced apart, at their outer ends, a greater distance than at the bend 2, incident to the springy nature of the metal. One side of each limb 3 is straight transversely as at 4, while the opposite side is inclined 45 transversely as at 5 and the outer

edges of the inclined sides merge into the corresponding edges of the straight sides to form relatively thin edges 6. The free extremities of the limbs 3, 3 are preferably beveled off as at 7, while the bent portion 2 of the metal is preferably circular in cross section.

In practice, when it is desired to apply the stretcher to a necktie the free ends of 55 the limbs 3, 3 are grasped in the hand and drawn together against the action of the metal. The bent portion 2 of the stretcher is now inserted in the tie and after the 60 stretcher has been passed into the tie the desired distance the limbs 3, 3 are released and expanded, thereby stretching the fabric of the tie and eliminating wrinkles. When inserting the device in the necktie the straight sides 4 of the limbs are disposed 65 against the inner surface of the outer side of the tie in order to effectively eliminate the wrinkles, while the inclined side of the limbs engage against the inner surface of the back portion of the tie. As the bent portion 2 70 of the metal is circular in cross section, it will be seen that the device may be readily and quickly inserted in the tie without mutilating the latter.

I claim:

As a new article of manufacture, a tie stretching device constructed from a single length of resilient material, and comprising spaced legs connected by the intermediate portion of the material which is circular in cross section, each of said legs being relatively broad and having a flat uninterrupted upper side through its entire area, and its lower side beveled or inclined to the outer longitudinal edge thereof for 85 the purpose described.

In testimony whereof I affix my signature in presence of two witnesses.

JOHN R. JOHNSON.
